CLAIM

The ornamental design for a folding matchbook, substantially as shown and described.

DESCRIPTION

FIG. 1 is a perspective view of a folding matchbook embodying my new design and depicted in a closed position;

FIG. 2 is a front elevation view thereof;

FIG. 3 is a left side elevation view thereof;

FIG. 4 is a right side elevation view thereof;

FIG. 5 is a rear elevation view thereof;

FIG. 6 is a top plan view thereof;

FIG. 7 is a bottom plan view thereof;

FIG. 8 is a perspective view of the design in a partially open position; and

FIG. 9 is a perspective view of an alternative form of my new design shown in an open position and including an extended lower flap but otherwise identical to the form illustrated in FIGS. 1-8.
